US00D658059S

(12) **United States Design Patent**
Bailey

(10) **Patent No.:** **US D658,059 S**
(45) **Date of Patent:** **** Apr. 24, 2012**

(54) **DISPOSABLE FOAMING ESPRESSO DRINK LID**

D543,777 S * 6/2007 Seum et al. D7/392.1
D544,749 S * 6/2007 Seum et al. D7/392.1
D592,056 S * 5/2009 Tedford, Jr. D9/447

(75) Inventor: **Craig Bailey**, Camas, WA (US)

* cited by examiner

(73) Assignee: **Foam Aroma LLC**, Camas, WA (US)

Primary Examiner — Susan Bennett Hattan

(**) Term: **14 Years**

(74) *Attorney, Agent, or Firm* — Mark E. Beatty; Kurt M. Rylander; Rylander & Associates, PC

(21) Appl. No.: **29/396,206**

(57) **CLAIM**

(22) Filed: **Jun. 27, 2011**

The ornamental design for a disposable foaming espresso drink lid, as shown and described.

(51) **LOC (9) Cl. 09-07**

DESCRIPTION

(52) **U.S. Cl. D9/447; D9/454**

FIG. 1 shows a top plan view.

(58) **Field of Classification Search** D9/772,

FIG. 2 shows a bottom plan view.

D9/454, 450, 449, 447, 438, 436, 435, 434;
D7/396.2, 392.1; 220/713, 711, 703, 377,
220/273, 270, 256.1, 254.1

FIG. 3 shows a front (drinking side) edge view.

See application file for complete search history.

FIG. 4 shows a back edge view.

(56) **References Cited**

FIG. 5 shows a right edge view.

U.S. PATENT DOCUMENTS

FIG. 6 shows a left edge view.

D369,109 S * 4/1996 Proshan D9/447
D415,027 S * 10/1999 Blazar D9/447
D478,006 S * 8/2003 Smith et al. D9/447

FIG. 7 shows a top perspective view.

FIG. 8 shows a bottom perspective view; and,

FIG. 9 shows a front perspective view.
